DESIGN FOR A COMBINED CONTAINER CARRIER AND DISPLAY DEVICE

Ellis M. Houghton, Marion, Ohio, assignor to
Double Duty Products, Inc., Cleveland, Ohio, a
corporation of Ohio

Application February 21, 1942, Serial No. 105,945

Term of patent 14 years

To all whom it may concern:

Be it known that I, Ellis M. Houghton, a citizen of the United States and a resident of Marion, in the county of Marion and State of Ohio, have invented a new, original, and ornamental Design for a Combined Container Carrier and Display Device, of which the following is a specification, reference being had to the accompanying drawing, forming a part thereof.

In the drawing: Fig. 1 is a front elevational

view of a combined container carrier and display device, showing my design; Fig. 2 is a right side elevational view; Fig. 3 is a left side elevational view; Fig. 4 is a bottom plan view; and Fig. 5 is a top plan view thereof.

I claim:

The ornamental design for a combined container carrier and display device, substantially as shown.

ELLIS M. HOUGHTON.
